CLAIM

The ornamental design for a massage chair, as shown and described.

DESCRIPTION

FIG. 1 is a front elevational view of a massage chair showing our new design, wherein a foot rest of the massage chair is in a first position;

FIG. 2 is a rear elevational view thereof, wherein the foot rest of the massage chair is in the first position;

FIG. 3 is a right side view thereof, wherein the foot rest of the massage chair is in the first position;

FIG. 4 is a left side view thereof, wherein the foot rest of the massage chair is in the first position;

FIG. 5 is a front, right side perspective view thereof, wherein the foot rest of the massage chair is in the first position;

FIG. 6 is a front, left side perspective view thereof, wherein the foot rest of the massage chair is in the first position;

FIG. 7 is a front elevational view thereof, wherein the foot rest of the massage chair is in a second position;

FIG. 8 is a rear elevational view thereof, wherein the foot rest of the massage chair is in the second position;

FIG. 9 is a right side view thereof, wherein the foot rest of the massage chair is in the second position;

FIG. 10 is a left side view thereof, wherein the foot rest of the massage chair is in the second position;

FIG. 11 is a front, right side perspective view thereof, wherein the foot rest of the massage chair is in the second position; and,

FIG. 12 is a front, left side perspective view thereof, wherein the foot rest of the massage chair is in the second position.

The broken lines shown in the drawing views are included for illustrative purposes only, and form no part of the claimed design.
